UNITED STATES PATENT OFFICE.

WILLIAM A. BRADLEY, OF OSHKOSH, WISCONSIN.

SHINGLE-MACHINE.

SPECIFICATION forming part of Letters Patent No. 271,407, dated January 30, 1883.

Application filed September 29, 1882. (No model.)

To all whom it may concern:

Be it known that I, WILLIAM A. BRADLEY, of Oshkosh, in the county of Winnebago and State of Wisconsin, have invented a new and 5 useful Improvement in Shingle-Machines, of which the following is a full, clear, and exact description.

My invention consists of improvements in the driving-gear, also in the bolt-dogging apparatus, and also in the bolt-setting apparatus of shingle-sawing machines, as hereinafter fully described.

Reference is to be had to the accompanying drawings, forming part of this specification, in 15 which similar letters of reference indicate corresponding parts in all the figures.

Figure 1 is a plan view of a shingle-machine constructed according to my invention. Fig. 2 is a side elevation with some of the parts in 20 section. Fig. 3 is a transverse section on the line $x-x$, Fig. 1. Fig. 4 is a section of the bolt-carriage on the line $y-y$, Fig. 3; and Fig. 5 is a section of the setting apparatus, taken on the line $z-z$ of Fig. 3.

25 For the purpose of simplifying the driving-gear and preventing all slack and lost motion of the carriage in running and on the back-stroke, I propose to dispense with toothed wheels altogether and employ a belt-pulley, a , on the saw-arbor i , for the first part of the reducing-gear to work the feed-motion, from which pulley the driving-belt b works onto the large pulley d of the counter-shaft e , which carries a small driver, f , from which the belt g 30 works onto the large pulley h of the feed-shaft c . A tightener, $k l m$, will be used with the belt b for producing the necessary tension to drive the feed-gear, and for slackening the belt to allow the feed to stop, when required, without 35 stopping the saw-shaft, on the top of which the saw j is mounted by the collar k' . The main belt runs on the pulley a' for driving the saw.

Only a single machine is shown in this case; 45 but by the extension of the frame to the left hand of the main feed-shaft, and the duplication thereon of the mechanism shown, except shaft e , the machine will be made double, which is the intention in practice.

50 The feed-shafts e and e and the saw-arbor i are arranged in suitable steps, n , in the bed-

timbers of the frame; and to operate the bolt-carriage o for sliding it forward and backward in the guides p to feed the bolts to the saw, I propose to apply the eccentric q to the upper end of the feed-shaft e to work the yoke-lever s , fixed on a pivot at t to vibrate so as to reciprocate the carriage by its swinging end u , to which the carriage is connected by a suitable rod, v . This makes a smooth-working device, entirely free from shocks and jars by the backlash of slack gears.

For dogging the bolt I use a sliding dog plate or bar, w , fixed in guides x in one end of the carriage, with a spring, y , to cause it to 65 grip and hold the bolt, and also with a rod, z , forming a support to the spring, and having a stud, a' , by which the dog is automatically detached from the bolt for resetting said bolt by the inclined arm b' , along which the stud a' is 70 moved by the carriage in the latter part of its back-stroke, so as to free the bolt from the dog and allow the bolt to fall on the table c' , on which it rests and slides until by the forward motion of the carriage the stud a' passes off 75 from the inclined arm b' , and the spring y again causes the dog-bar to grip the end of the bolt. Said bar may have any suitable arrangement of spur studs or points to penetrate the block sufficiently to insure a firm hold. 80 Thus the bolts are automatically shifted and set for the successive cuts. The object of locating the dog slide guides on the top of the carriage is to place them and the spring and stud so far above the saw that they will not be 85 clogged by the sawdust.

In order to cause the resetting of the bolts, so as to alternately cut butts and points at the respective ends of the bolts, the bars c' , forming the table whereon the bolts fall and rest 90 in the resetting operation, are mounted on the bars d' , pivoted at the center of the table, at e' , to the head f' of vertical standard g' , said bars ranging therefrom toward the respective sides of the machine, and resting, when in their normal position, on the temper-screws h' at their outer ends, said temper-screws being fitted adjustably in the cross-bar i' , supported on the standard g' by the collar j' . The respective sides of the table thus supported and pivoted 95 may therefore be raised and lowered to tilt the bolt, or, rather, cause it to assume an inclined

position when it falls, one end falling lower than the other; and in order to alternately shift the respective sides of the table for alternating the butts and points of the shingles 5 the bars d' are formed with inclines k' on the lower side, and wedges l' are mounted on a sliding bar, m' , under them, which are shifted each time the carriage goes forward by the zigzag cam-disk n' , which works between the 10 studs o' on said bar m' , and is worked by the catch-pawl p' , pivoted to the carriage so as to engage one of the stud-pins q' of the disk each time the carriage goes forward to the saw, and shifts the cam-disk to the extent of one of the 15 inclines of the disk, thus reversing the movement of the slide at each motion of the carriage and alternately lifting the opposite sides of the table c' . The catch-pawl p' is provided with a lever handle, t' , by which to lift it up 20 so as to set the pin u' under it, and hold it out of engagement with the disk n' when it may be desired to cut the shingles in uniform thickness. The wedges l' are slotted for their fastening bolts w' , in order that they may be shifted 25 forward and backward along the bar to raise the sides of the table more or less, to vary the thickness of the butts and points of the shingles as may be required. The standard g' is adjustable by the screw-nuts x' and support- 30 ing-bar y' to vary the height of the table.

Having thus described my invention, I claim as new and desire to secure by Letters Patent—

1. In a shingle-machine, the combination, with the saw-arbor i , provided with the pulley a , and the feed-shaft c , provided with the pulley h , of the counter-shaft e , provided with the pulleys $d f$, the belts $b g$, and the belt-tightener $k l m$, substantially as and for the purpose set forth.

2. In a shingle-machine, the combination, with the bolt-carriage o , of the table $c' d'$, composed of two parts hinged together, and means,

substantially as herein shown and described, for alternately raising and lowering the sides of the table, as set forth.

45

3. In a shingle-machine, the combination, with the table $c' d'$, composed of two parts hinged together and having inclines k' on its under surface, of the shifting bar m' , provided with the wedges l' , and means, substantially as shown and described, for operating said shifting bar, as set forth.

50

4. In a shingle-machine, the combination, with the table $c' d'$, composed of two parts hinged together and having inclines k' on its under surface, of the bar i , the temper-screws h' , the shifting bar m' , provided with wedges l' , and means, substantially as shown and described, for operating said shifting bar, as set forth.

55

5. In a shingle-machine, the combination, with the adjustable standard g' , provided with the head f' , of the table $c' d'$, composed of two parts hinged together and pivoted at its center to the said head, and the temper-screws h' , substantially as and for the purpose set forth.

60

6. In a shingle-machine, the combination, with the table $c' d'$, composed of two parts hinged together and provided with the inclines k , of the shifting bar m' , provided with the wedges l and the studs o' , the zigzag cam-disk n' , provided with the pins q' , and the pawl p' , substantially as and for the purpose set forth.

65

7. In a shingle-machine, the combination, with the table $c' d'$, composed of two parts hinged together and provided with the inclines k' , the cross-bar i , and adjustable support g' , of the sliding bar m' , provided with wedges l' , and the zigzag cam-disk n' , substantially as and for the purpose set forth.
